SOUND RECORDING AND REPRODUCING
SYSTEM

Stuart W. Seeley, Jackson, Mich., assignor, by direct and mesne assignments, to Radio Corporation of America, New York, N. Y.

Original application January 19, 1931, Serial No. 509,693. Divided and this application April 15, 1935, Serial No. 16,296

2 Claims. (Cl. 179—100.4)

This invention relates to improvements in sound recording and reproducing systems, and is a division of my copending application Serial No. 509,693 filed January 19, 1931.

5 In the present day art of recording sound, particularly on disc records, it is well known that the cutting mechanism used in making such records must, of necessity, be so governed that the lateral velocity of the cutting tool is not absolutely proportional to the applied voltage at all frequencies. This is because of the fact that the lower frequencies tend to overlap from one groove to the other and thus cause the reproducing needle to jump from one groove to the 10 next. An examination of records designed to give constant output at various frequencies in the audio band, discloses the fact that the amplitude of the wave form of the track is approximately inversely proportional to the frequency. 15 and thus the lowest notes to be reproduced must be attenuated before entering the cutting tool in order that the amplitude of the wave form of the path would not be too great.

It is also well known in the art that the 20 production of phonograph records is invariably accompanied by a certain amount of surface noise or what is commonly known as record scratch. If this is allowed to remain in the reproduced sound, it is exceedingly objectionable 25 and if it is removed by means of electrical or mechanical filters, certain desirable portions of the recorded frequencies are lost.

I have found that by unbalancing the frequency gain curve of both the recording apparatus and the reproducing apparatus in such a way that the resultant output of the reproducing apparatus is substantially uniform over the whole frequency range, the difficulties due to non-uniformity of frequency response and record scratch 30 are substantially overcome.

It is commonly known that the tonal scale of the ear is a logarithmic function of the frequency and, therefore, if the audio frequency spectrum consists of frequencies of from 50 cycles 35 to 5,000 cycles, 500 cycles will be the central point or the half-way mark of such a tonal scale. Thus, we see that the lower portion of the audio frequency spectrum consists of frequencies varying from 50 to 500 cycles or a difference of 450 cycles, while the upper half of the audio frequency spectrum consists of frequencies from 500 40 to 5,000 cycles or a difference of 4,500 cycles.

It is also known that the surface noise accompanying a sound record consists of sound frequencies fairly evenly distributed throughout 45

the audio frequency spectrum and, therefore, if 500 cycles represents the half-way mark on the tonal scale, substantially 90% of the disturbing frequencies will be present in the upper half of the audio frequency spectrum. From a study 5 of the physiological characteristics of the ear, it is known that interference in the upper half of the audio spectrum is more objectionable than interference in the lower half of the spectrum. This is because of the well known fact that the 10 threshold value of audibility of the human ear is far higher at the lower frequencies than at the frequencies ranging from 1,000 to 5,000 cycles. It is, therefore, desirable to eliminate particularly 15 the interference present in the upper half of the audio spectrum.

I have found that the difficulties due to non-uniformity of response and to surface noise can be substantially overcome by raising the energy level, during the recording process, of the higher 20 frequencies of the audio spectrum to a point well above the energy level of the surface noise in that region. This may be accomplished by using an amplifier ahead of the record cutting tool having a rising gain characteristic with the frequency. Then, in order to facilitate a flat frequency response in the reproducing system, I propose to utilize an amplifier following the record 25 pick-up in which the gain is approximately inversely proportional to the frequency. Since the 30 lower frequencies of the sound to be recorded normally impart a greater amplitude of wave form to the cutting tool than would the higher frequencies, it is at once apparent that the use 35 with the frequency, will produce a record of substantially constant amplitude of track wave thereby permitting a closer spacing of the sound grooves than was heretofore practical.

The main object of my invention is to provide 40 a sound recording and reproducing system capable of producing a substantially uniform response over the entire frequency range of the reproduced sound.

It is a further object of my invention to provide 45 a sound recording and reproducing system that reduces record surface noise to a minimum.

It is also an object of my invention to provide 50 a sound recording system that gives a record of constant amplitude of track wave as distinguished from records of present systems giving constant voltage of pick-up.

Other objects and advantages of the invention 55 relate to the particular circuit arrangement of my apparatus and will appear more fully in the

following description taken in connection with the accompanying drawings in which:—

Figure 1 is a schematic view of my recording system;

5 Figure 2 is a schematic view of my reproducing system;

Figure 3 shows the gain curve of the audio frequency amplifier used in the recording system;

10 Figure 4 shows the gain curve of the audio frequency amplifier used in the reproducing system; and

Figure 5 shows the resultant output characteristic of the reproducing system.

Referring to the drawings, the reference character 1 designates a microphone for picking up the sound to be recorded. An amplifier 2 amplifies the microphone current and feeds the same into a special amplifier comprising a vacuum tube 3 and the necessary coupling units to produce 20 a rising gain characteristic. The tube 3 may be of the well known screen grid type having an amplification factor of approximately 400 and a mutual conductance of about 1,000.

The output circuit of the tube 3 includes resistance 4, inductance 5 and a blocking condenser 6 which is used to prevent the passage of direct current through the inductance 5 from the 250 volt source used to energize the plate of tube 3. Inductance 5 is of such a value that the total 30 output impedance of tube 3 does not vary over 2% from 50 to 5,000 cycles. Connections 7 and 8 are taken across inductance 5 and lead to the input of a succeeding tube included in amplifier 12. The input circuit to amplifier 12 comprises a 35 grid condenser 9, a grid resistor 10 and a conventional grid bias battery 11. The output of amplifier 12 is connected to a record cutting tool 13 which records the sound waves on a wax record 14 which may be rotated by a turntable 15 in 40 any conventional manner.

In practice, I have used a resistance of 600,000 ohms for resistance 4 and a coil 5 having 1.59 henries inductance. Such an inductance has approximately 50,000 ohms impedance at 5,000 45 cycles. As shown in Figure 3, this special stage shows a gain of about 20 units at 5,000 cycles and 0.2 unit at 50 cycles or a variation of about 40 decibels. The gain of tube 3 in connection with the above described circuit will be

50

$$\frac{Mu w L}{(Rp+r)wc}$$

which indicates a rising gain characteristic. In 55 this formula, Mu is equal to the voltage amplification of the tube, w is equal to 2π times the frequency being amplified, L is the inductance of coil 5, Rp is the internal plate impedance of the tube and r is the value of the external resistance 4.

60 It will be noted that the input voltage to amplifier 12 is taken across the inductance 5 in the output circuit of tube 3. Thus, the input to the amplifier 12 will be proportional to the voltage drop across this coil. This voltage will vary approximately in accordance with the above formula expressing the gain of the circuit. In the formula, Mu, L, Rp and r remain substantially constant over the frequency range from 50 to 65 5,000 cycles. The term w , which is $2\pi f$, will vary directly with the frequency f being amplified. Thus, the gain will be directly proportional to the frequency from 50 to 5,000 cycles when 70 using the constants above mentioned. A rising 75 gain characteristic with frequency of the special

amplifier above described, will eliminate the tendency to overcut the record at the lower frequencies thereby permitting a closer grooving of the record than was heretofore practical.

In order to obtain a flat frequency response in 5 the reproducing system, I propose to use a circuit arrangement as shown in Figure 2. A permanent disc record as 16 may be made from the wax record 14 in any manner well known in the art. The record 16 may be rotated by a turntable 17 of suitable design. A pick-up device 18 may be conveniently connected to amplifier tube 20 by means of transformer 19. The tube 20 is of the screen grid type and, in this instance, may have characteristics similar to that of the tube 3 15 in the recording apparatus. The value of resistance 21 that I have chosen may be 600,000 ohms and the capacity of condenser 22 is such that the output circuit of the tube 20 maintains practically constant impedance throughout the 20 audio band. This capacity has been found in practice to be equal to .064 mfd. and has an impedance of approximately 50,000 ohms at 50 cycles.

The input to the succeeding amplifier tube of 25 amplifier 28 is taken by means of leads 23 and 24 across the condenser 22. In addition, this input circuit also includes a conventional grid coupling condenser 25, a grid resistor 26 and a grid bias battery 27. The output of amplifier 28 may be 30 connected in the usual manner to a reproducing device or loud speaker 29.

From the circuit diagram shown in Figure 2, it is apparent that the gain of the special amplifier stage in the recording apparatus is represented by the formula

$$\frac{Mu}{(Rp+r)wc}$$

where Mu is equal to the voltage amplification of 40 the tube 20, Rp is the internal plate impedance of the tube, r is the value of the external resistance 21, w is equal to 2π times the frequency being amplified and c is the value of the capacity 22.

45 It will be noted that the input voltage to amplifier 28 is taken across the condenser 22 in the output circuit of the tube 20. The voltage drop across the condenser 22 is proportional to the output of the tube 20 as given in the approximate formula above. In the formula, Mu, Rp, r , and c remain approximately constant throughout the frequency range from 50 to 5,000 cycles. The term w which is $2\pi f$, will vary directly with the frequency f being amplified. Now then, since 55 the gain of the tube 20 varies inversely with the frequency, then as the frequency increases, the voltage drop across the condenser 22 will decrease.

Using the constants given in the previous discussion and calculating the gain by means of the 60 formula, we find that the gain varies from 20 units at 50 cycles to 0.2 unit at 5,000 cycles or a loss of 40 decibels at 5,000 cycles over the 50 cycle level. The gain characteristic of this amplifier is shown in Figure 4 and it will be noted 65 that this characteristic is just the reverse of the gain characteristic of the recording amplifier. It is, therefore, apparent that the resultant response at the loud speaker will be of the form shown by the curve in Figure 5. This is what is 70 commonly called a flat frequency response and is the ultimate characteristic sought by sound engineers.

75 As pointed out above, in the conventional method of cutting records, the amplitude of the

track wave is approximately inversely proportional to the frequency of the recorded sound, and the track wave amplitude for the lower frequencies is greater than that for the higher frequencies. When reproduced electrically, these records therefore produce a substantially constant voltage of pick-up. In recording with the present invention, on the other hand, the amplification is directly proportional to the frequency of the sound to be recorded, so that the higher frequencies are amplified proportionately more than the lower frequencies, resulting in a substantially constant amplitude of the track wave. This eliminates the tendency present in the conventional system to overcut the record at the lower frequencies, and the present invention therefore permits a closer grooving of the record than was heretofore practical. Most of the objectionable record scratch is present at the higher frequencies, and the rising gain with frequency characteristic of the amplification of the present invention during recording results in raising the energy level of the higher frequencies of the recorded sound relative to the energy level of the record scratch. When the record so made is reproduced according to the present invention, therefore, using an amplifier having a gain characteristic inversely proportional to the frequency of the recorded sound, not only is a uniform or flat frequency response over the entire frequency range of the recorded sound obtained for the system as a whole, but the undesirable record scratch is reduced to a minimum without impairing the quality of the reproduced sound because the record scratch occurs largely at high frequencies which are amplified after pick-up only relatively little and because it is present in the record at a low energy level as compared to the desired recorded sounds of similar frequency.

It is to be understood that the specific apparatus herein disclosed is merely for the purpose of

illustrating my invention as changes and modifications may be made by those skilled in the art without departing from the spirit and scope of the appended claims.

I claim:

1. In a sound recording system, means for translating the sound to be recorded into electrical waves, an amplifier for amplifying said electrical waves, said amplifier having at least one vacuum tube and having an output circuit including a resistance, a condenser and an inductance in series, an electrically operated cutting tool, and means for actuating said cutting tool in accordance with the voltage variations across said inductance, the constants of said amplifier output circuit being such that the amplifier has a gain characteristic rising in direct proportion to the frequency of said electrical waves for producing voltage variations across said inductance such that the record track wave cut by said cutting tool has a substantially constant amplitude throughout the recorded frequency band.

2. In a sound reproducing system for the reproduction of permanent sound records having a substantially constant amplitude of track wave, means for producing electrical waves corresponding in frequency with the track waves on the record, an amplifier for amplifying said electrical waves, said amplifier having at least one vacuum tube and having an output circuit including a resistance and a condenser in series, and a translating device for producing sound actuated by the voltage variations across said condenser, the constants of said amplifier output circuit being such that the amplifier has a gain characteristic rising in inverse proportion with the frequency of the recorded waves for producing voltage variations across said condenser such that a substantially flat frequency response is obtained at the translating device.

STUART W. SEELEY.
